UNITED STATES PATENT OFFICE.

FRANK W. WATERMAN, OF BALTIMORE, MARYLAND, ASSIGNOR OF ONE-THIRD TO HERBERT E. GIBSON AND ONE-THIRD TO FREDERICK T. DORTON, OF BALTIMORE, MARYLAND.

COIN-CONTROLLED LIQUID-VENDING APPARATUS.

No. 846,366.

Specification of Letters Patent.

Patented March 5, 1907.

Application filed October 29, 1904. Serial No. 230,531.

To all whom it may concern:

Be it known that I, FRANK W. WATERMAN, a citizen of the United States, residing at Baltimore, in the State of Maryland, have invented new and useful Improvements in Coin-Controlled Liquid - Vending Apparatus, of which the following is a specification.

This invention relates to certain new and useful improvements in coin-controlled liquid-vending apparatus, and has for its principal object to provide a novel construction of parts rendered operable on the insertion of a coin into the machine for permitting a predetermined amount of liquid to be discharged from the apparatus.

Other objects of the invention relate to details of construction and to combinations and arrangement of parts coöperating with the aforesaid apparatus, whereby I am enabled to provide a machine of the character indicated which shall be simple and compact in construction, reliable in operation, and one which may be comparatively economically manufactured.

That which I claim as my invention will be indicated in the claims following the specification.

In order that the invention may be clearly understood, I have illustrated the same in the accompanying sheets of drawings, wherein—

Figure 1 is a cross-sectional view through the casing viewed from the rear thereof, the parts within the casing being shown in elevation. Fig. 2 is a transverse sectional view, on an enlarged scale, taken through the upper part of the casing and illustrating in elevation the coin-controlled mechanism. Fig. 3 is a sectional plan view, on a similar scale, of the parts shown by Fig. 2. Fig. 4 is a sectional plan view taken on the line 4-4 of Fig. 1. Fig. 5 is a detail sectional view of the valve, and Fig. 6 is a broken plan view showing the connection between the pull-rod and the coin-trough.

Similar reference-numerals indicate corresponding parts throughout the several views.

Referring now to the drawing, the apparatus as illustrated comprises a casing 1, the lower part of which is of a size adapted to receive a tank 2. For the purpose of permitting the ready entrance and removal of said tank the casing is preferably provided on one side with a hinged door 3. A truck 4 may be

provided to facilitate placing the tank within the casing, and a bracket 5 is located at one side of the casing to position the tank within the same. Removably connected with the tank 2, as by means of a jam-nut 6, is a pipe 7, provided with a valve 8. The casing 1 is divided by a partition 9 into two compartments, the lower compartment 10 containing the tank referred to above and the upper compartment 11 containing certain parts hereinafter referred to and being adapted also to contain ice.

The pipe 7 leads through the partition 9 into the upper compartment 11, in which compartment it is given the form of a coil 12 and is provided with a continuation 13, connecting with a closed vessel 14, hereinafter referred to as the "cooler." From the cooler 14 a pipe 15 leads to a two-way valve 16, which, together with the coin-controlled apparatus, is located in a housing 17, mounted on the casing 1. The valve 16 is shown in detail in Fig. 5, and, as there illustrated, comprises a plug 17, having near two opposite sides parallel passages 18 and 19, respectively. The casing 20 of the valve is shown to have four outlets, (indicated, respectively, by 21, 22, 23, and 24,) which are designed to be brought into communication in pairs with the respective passages 18 and 19, as herein-after described.

Mounted in the casing 1 above the coil 12 and cooler 14 are two measuring vessels 25 and 26, respectively. From the vessel 25 the pipe 27 leads to the valve 16, and from the valve 26 the pipe 28 leads to said valve. 29 indicates a pipe leading from the valve 16 through the wall of the housing 17, where it is bent downward to provide the faucet 30 for the discharge of the liquid into a suitable receptacle. In the arrangement shown the pipe 15, leading from the cooler, connects with port 23 of the valve-casing, the pipe 27, leading from the measuring vessel 25, connects with the port 24, the pipe 28, leading from the measuring vessel 26, connects with the port 22, and the pipe 29, leading to the faucet 30, connects with the port 21.

In the operation of the apparatus it is intended that one of the measuring vessels 25 or 26 shall be placed in communication with the faucet 30 to discharge its contents, while the other measuring vessel, which has pre-

viously been emptied, shall be simultaneously placed in communication with the cooler 14 to be refilled. The mechanism for operating the valve-plug 17 to this end will now be described.

5. The valve-plug 17 is provided with a spindle 31. Mounted on said valve-spindle to turn therewith is a ratchet-wheel 32, and loosely mounted on said spindle is a slotted 10 lever-arm 33, which carries a spring-controlled pawl 34, engaging with the said ratchet-wheel. To this end the lever-arm 33 is provided, intermediate its ends with two brackets 35, in which works a rod 36, carrying 15 said pawl, and coiled about said rod and located between the two brackets 35 is a spring 37, which normally operates to maintain the pawl in engagement with the ratchet-wheel.

20. 38 indicates a pull-rod provided on the outside of the housing with a knob 39 and intermediate its ends provided with a pin 40, working in a slot 41 in the lever-arm 33.

25. 42 indicates the coin-trough, which is pivotally supported at 43 near its inner end on a bracket 44, said inner end being weighted, as indicated at 45. The coin-trough is provided in its upper edge with a deep slot 46, in which the coins inserted in the machine 30. travel, and a coin-chute 47, leading from the outside of the housing 17, is arranged to deliver coins inserted therein into the slot 46 at the inner end of the coin-trough 42. Said coin-trough is provided on its inner side with a lug 48, which is normally engaged by a spring-controlled detent 49, carried by the pull-rod 38, as indicated more clearly in Fig. 3 and the detail view Fig. 6.

It will be understood that the engagement 40 of the detent 49 with the lug 48 prevents the pull-rod 38 from being drawn outward to operate the valve. When a coin 50 has been inserted in the machine, it rolls down to the outer end of the coin-trough, and its weight 45 is sufficient to overbalance said trough and carry its outer end downward, thereby moving the lug 48 out of engagement with the detent 49, so that the pull-rod 38 can be drawn outward by grasping the knob 39. In this 50 operation the pin 40, engaging in the slot 41, will operate to rotate the plug of the valve by reason of the engagement of the pawl 34 with a tooth of the ratchet-wheel 32, which is fixed on the spindle of said plug, and thereby 55 bring one or the other of the passages 18 19 in communication with the ports of the casting of the valve to permit one of the measuring vessels 25 to discharge its contents through the faucet 30 and to place the other 60 measuring vessel in communication with the cooler 14, so that the former may be refilled. Thus in the position of the parts shown by Figs. 1 and 5 the measuring vessel 25 is in communication through the port 19 with the 65 cooler 14, and the measuring vessel 26 is in

communication with the faucet through the port 18. In the inward movement of the push-rod 38 this position of the parts is unchanged, the pawl 34 riding over the ratchet-wheel until it comes into engagement with a fresh tooth thereon, four teeth being provided on said ratchet-wheel, so that in each movement of the pull-rod the valve-plug is given a quarter-turn. In the next movement outward of the pull-rod after the insertion of a fresh coin the valve-plug will be turned to place the passage 18 in communication with the pipes 27 and 29, so that the measuring vessel 25 will discharge through the faucet 30, and the passage 19 will be placed in communication with the pipes 15 and 28, so that the measuring vessel 26 may be refilled from the cooler 14. Thus the measuring vessels 25 and 26 will be alternately emptied and refilled.

It will be understood, of course, that the liquid in the tank 2 is maintained under pressure.

For retracting the pull-rod 38 I provide a relatively long leaf-spring 51; secured at one 90 end to the side of the housing 17 and at its other end to the said pull-rod intermediate the ends thereof, as indicated in Fig. 2. In the retractive movement of the pull-rod the detent 49 will ride over the lug 48 and resume 95 the position shown in Figs. 3 and 6.

Pivottally mounted adjacent to the end of the pivoted coin-trough 42 is a gate 52, normally held against the discharge end of the coin-trough by the action of a weight 53 on an arm 54, forming a part of said gate. The gate 52 is provided with a hub 55, by means of which it is pivoted in the outer end of a bracket-arm 56, suitably mounted in the housing. Extending upward and rearwardly 100 from the hub is an arm 57. Mounted on the outer end of the pull-rod 38 is a pin 58, which when the pull-rod is drawn outward is adapted to ride over the arm 57 and depress the same, and thereby move the gate 52 110 away from the end of the trough 42 and permit the coin 50 to fall. The purpose of this gate is to prevent the coin from falling from the trough, and thus permitting the latter to rise and bring its lug 58 in front of the detent 115 49 before the operator has had an opportunity of drawing out the pull-rod.

By the construction described it will be seen that the coin will rest in the coin-trough and hold the lug 48 below the detent until the 120 person using the machine has had an opportunity of drawing out the pull-rod. A suitable receptacle 59 may be provided for receiving the coins as they fall from the coin-trough.

Having thus fully described my invention and the manner of operating the same, I declare that what I claim as new, and desire to secure by Letters Patent, is—

1. An apparatus of the class described, in- 130

volving a coin-chute, a tilting coin-receiving trough pivotally connected near one end thereof to a case and having a deep slot throughout its extent, a weight at the pivotal 5 end of the trough, a lug extending from one side of the coin-receiving trough, a pull-rod having a spring-controlled detent for engagement with the lug to normally lock the rod against movement, a spring for returning the 10 pull-rod to its normal inoperative position, and a pivotally-mounted gate normally held against the discharge end of the coin-trough, an arm carried by said gate, and means on 15 said pull-rod adapted to engage the arm to release the gate upon movement of the pull-rod in one direction to allow the discharge of the coin from the coin-trough.

2. In an apparatus of the class described, a pivotally-mounted coin-trough having a 20 depending weight at one end thereof and a deep slot extending throughout its longitudinal extent, a lug projecting from said trough, a pull-rod, a spring-controlled detent carried by the pull-rod and normally in engagement 25 with the lug on the coin-trough to hold the pull-rod against movement, a pivotal gate mounted at the discharge end of the coin-trough for preventing the release of the coin from said trough until the gate is actuated, 30 an arm on said gate, a pin carried by the pull-rod for engagement with the arm to operate the gate for releasing the coin from the trough, and a spring for holding the pull-rod in locking engagement with the coin-trough.

3. In an apparatus of the class described, a tiltable coin-receiving trough, a pull member, said trough being provided with means to normally prevent advancing movement of 35 said pull member and tiltable from its normal position by the action of a coin or equivalent device to release said pull member, a gate to temporarily retain the coin or equivalent device in said trough and means coöperative with the pull member for operating 40 said gate on the advancing movement of said pull member to release the coin from said trough.

4. In an apparatus of the class described, a tiltable coin-receiving trough, a pull member, said trough being provided with means 45 to prevent advancing movement of the pull

member when said trough is in its normal position, said trough being tiltable from said normal position by the action of a coin or equivalent device, a gate to positively and 50 temporarily hold said coin or equivalent device in said trough to insure the tilting movement thereof, means for positively holding said gate in its effective position and means connected with the pull member for causing 55 the operation of the gate to release the coin or equivalent device on the advancing movement of said pull member.

5. In an apparatus of the class described, a tiltable coin-receiving trough, a pull member, said trough being tiltable from a normal 60 position by the action of a coin or equivalent device and being provided with means to prevent the advance movement of the pull member when the trough is in its normal position, 65 the latter having a slot open at one end for the discharge therefrom of the coin or equivalent device, a gate, means connected with the gate for normally holding the same against the delivery end of said slot to thereby 70 temporarily retain the coin or equivalent device in the trough, and means coöperative with the pull member for swinging the gate open on the advancing movement of said 75 pull member to release the coin from the trough.

6. In an apparatus of the class described, a pull member, a trough movable from a normal position by the action of a coin or equivalent device, said trough being provided with 80 means to positively hold the pull member against movement when said trough is in its normal position and operable by said coin or equivalent device to release the pull member, a gate to retain temporarily the coin in said 85 trough to insure the releasing movement of said pull member, and means controlled by the pull member for operating the gate to release the coin therein.

In testimony whereof I have hereunto set 90 my hand in presence of two subscribing witnesses.

FRANK W. WATERMAN.
